UNITED STATES PATENT OFFICE

2,240,316

HEATER

Thomas F. Spackman, Chicago, Ill., assignor to
Stewart-Warner Corporation, Chicago, Ill., a
corporation of Virginia

Application September 22, 1938, Serial No. 231,232

2 Claims. (Cl. 257—137)

The present invention relates generally to heaters and the like, and more particularly to a combined mounting and air supply construction for heaters mounted upon partitions.

One of the objects of the invention is to provide an improved heater mounting for internal combustion heaters or the like.

Another object of the invention is to provide an improved fresh air supply for automobile heaters.

Another object of the invention is to provide a combined unitary mounting and fresh air supply which requires the drilling of only one hole in the dash of an automobile or other or similar partitions.

Another object of the invention is to provide a combined and improved fresh air supply conduit construction and control therefor.

Another object of the invention is to provide a device of the class described, which is simple in construction and operation, thoroughly effective in its use, and inexpensive to manufacture.

These being among the objects of the invention, other and further objects will become apparent from the drawings herein, the description relating thereto, and the appended claims.

Referring now to the drawings:

Fig. 1 is a side elevation partly in section, illustrating a preferred form of the combined mounting and fresh air supply constituting the subject matter of the present invention;

Fig. 2 is a top plan partly in section, of the construction illustrated in Fig. 1;

Fig. 3 is a section taken upon the line 3—3 of Fig. 2; and

Fig. 4 is a section taken upon the line 4—4 of Fig. 1.

Referring now to the embodiment of the invention illustrated, the heater is indicated generally by the numeral 18, and reference may be had to the copending application of Henry J. De N. McCollum, Serial No. 61,213, filed January 28, 1936, for the structural characteristics thereof, wherein, briefly, air is drawn by the fan 12 and motor 14 into the fan compartment 16 of the heater shell 18 through the intake opening 28, forced through the radiator 24 in heat exchange relationship therewith, and driven out into the interior of the passenger compartment through the downwardly opening bell-shaped outlet 26.

The radiator 24 receives its heat from the hot gases of combustion derived from a combustible mixture that is supplied by the carburetor 28 and ignited in the combustion chamber 30, and

the fan 12 and motor 14 are supported immediately above the radiator 24 by a back plate 22.

The opening 28 is provided in the back plate 22 while the combustion chamber, the mixing chamber 32, and the outlet conduit 34 are all cast as an integral unit 33 which is secured to the back plate 22 in union with the radiator 24 through a second hole 23 in the back plate 22.

Considering the right of the heater as shown in Figs. 1 and 2 as the back portion, a stamping 36 is secured to the back of the back plate 22 and covers substantially the entire area thereof to provide a housing with a rearward wall 40 thereof spaced from the back plate 22. A circular opening 42 is provided in the back wall 40 and the dimension of this opening is substantially greater than the gross contour of the unit 33 where it passes through the opening 42, so that the clearance thus provided between the margin of the opening 42 and the unit 33, affords a passageway through which air may pass from outside the stamping 36 into the shell 18 in heat exchange relationship with the unit 33.

In mounting the heater, an opening 44 is cut in the dash 46 of the same size as the opening 42, and the open end of a cylindrically walled cup 48 is inserted therethrough to a point where a circumferential upset providing an outwardly extending flange 50 engages the metal sheathing 52 located upon the engine side of the dash 46.

The closed end 54 of the cup member has stamped openings 56 and 58 therein to receive the end portions of the mixing chamber 32 and the exhaust conduit 34 when the cup member is installed. The exhaust conduit 34 is threaded to receive the nut and washer assembly 60 thereon which, when tightened, press against the closed end 54 in cooperation with the flange 50 to press same against the dash and draw the heater into place against the passenger compartment side of the dash with a suitable metal plate 62 located between the back wall 40 of the stamping and the dash 46. In this way the heater is readily installed and held firmly in place.

An opening 64 as more particularly shown in Figs. 3 and 4, is provided in the cylindrical wall of the cup member 48 between the end wall 54 thereof and the flange 50, and this opening is covered on the outside by a sheet metal member 66 secured upon both sides of the opening, as by welding, indicated at 68. The member 66 leads to a source of fresh air through an intake conduit 70 so that fresh air may be supplied to the heater from the intake conduit 70, through the

sheet metal member 66 and through the opening 48.

A sleeve 72 is located upon the inside of the cup member, and an opening 74 is provided therein to coincide with the opening 64 when in one relative position, as rotated inside the cup 48, and to close the opening varying degrees to control the amount of fresh air admitted from the conduit 78. In order to operate this cylindrical valve arrangement, a bar 76 is secured to the sleeve 72 and extends to a point within the confines of the stamping 36, where an arm 78 is threadedly secured thereto. The arm 78 extends through a transverse slot 80 in the bottom of the stamping 36 and is provided with a handle 82 at the end thereof for manipulation so that movement of the handle 82 through an arc substantially in excess of 90 degrees will control the amount of fresh air entering into the fan and motor compartment 16.

In event the fresh air supply is entirely shut off by the cylindrical valve sleeve a substantial amount of air still may be drawn through the slot, which is made of a sufficient width not only to prevent a rattling contact between the arm 78 and the slot 80, but to admit enough air from the interior of the passenger compartment to maintain adequate recirculation.

In this way the amount of fresh air supplied for passenger comfort may be controlled and is 30 circulated over the combustion unit in heat exchange relationship to be pre-warmed by heat which otherwise would be wasted. The pre-warmed air is then circulated by the fan over the radiator out into the interior of the passenger compartment, and in this connection it will be noted that the pre-warming of the fresh air makes it possible to substitute the fresh air for the recirculated air without noticeable change with regard to the temperature of the air being 40 supplied by the heater.

Moreover, the combined unitary mounting and fresh air supply provided for internal combustion heaters is simple in construction and operation, effective in its use and inexpensive to manufacture, and, although a single embodiment of the invention has been shown and described herein, it will be apparent to those skilled in the art that various and further uses, modifications and changes may be made without departing from the spirit and substance of the invention, the scope of which is commensurate with the appended claims.

What is claimed is:

1. In combination with a forced circulation air heater mountable in an opening in a wall and having an air inlet opening and an independent combustion heat exchange unit, a cup member receivable in said wall opening and apertured at its closed end to receive one end of said unit therethrough with the cup opening towards the opposite end of said unit, a flange on said cup member providing a shoulder abutting said wall around said wall opening, a stamping secured to said heater to provide a housing over said inlet opening and having an opening in a wall thereof for receiving the open end of said cup member therethrough, whereby said stamping and said cup member are in open communication with each other for the passage of air from one side of the wall to the other, means engaging said one end of said unit and the closed end of said cup member for drawing said stamping and said cup member towards each other on opposite sides of said wall for supporting said heater on said wall, said cup member having an opening admitting said air, and manual means for controlling the flow of said air through the last said opening.

2. In combination with a forced circulation air heater mountable in an opening in a wall and having an air inlet opening and an independent combustion heat exchange unit, a cup member receivable in said wall opening and apertured at its closed end to receive one end of said unit therethrough with the cup opening towards the opposite end of said unit, a flange on said cup member providing a shoulder abutting said wall around said wall opening, a stamping secured to said heater to provide a housing over said inlet opening and having an opening in a wall thereof for receiving the open end of said cup member therethrough, whereby said stamping and said cup member are in open communication with each other for the passage of air from one side of the wall to the other, means engaging said one end of said unit and the closed end of said cup member for drawing said stamping and said cup member towards each other on opposite sides of said wall for supporting said heater on said wall, said cup member having an opening admitting said air, and said stamping having an elongated opening to admit air to said inlet opening from the same side of said wall, and cylindrical valve means accessible through said elongated opening for controlling the flow of air through said opening in the cup member.

THOMAS F. SPACKMAN.
